UNITED STATES PATENT OFFICE

JULIUS GLUCK, OF PARIS, FRANCE, ASSIGNEE, BY MESNE ASSIGNMENTS, TO OHMER FARE REGISTER COMPANY, OF DAYTON, OHIO, A CORPORATION OF NEW YORK

TAXIMETER CONSTRUCTION

Application filed July 3, 1924. Serial No. 724,145.

This invention relates to taximeters of the type used on cabs or other public vehicles for automatically registering the tariff to be collected from the passenger.

5 To that end the invention has generally in view a simple, compact and reliable construction involving a minimum number of parts and which is easy to manufacture and assemble. In that connection the invention 10 contemplates a meter wherein the drive shaft is arranged to conveniently operate suitable counter devices and the cam shaft is divided into two sections which permits of arranging the different parts thereof at right angles to 15 effect a maximum economy of space. Also it is proposed to provide a group of counters for registering the various data desired including what is known as a detector counter, namely, a device for determining the operation of the vehicle with the flag in an improper position.

In addition to the foregoing general object the invention contemplates a novel and practical form of flag lock which does away 25 with the necessity of having a separate manually operated flag locking key or knob, the flag being automatically locked at the end of each complete cycle, and capable of being unlocked by a partial reverse movement at 30 the beginning of the new cycle.

Another object is to provide a novel resetting mechanism for resetting the fare drums as well as the star wheel unit and to also hold the fare drums as well as the star 35 wheel positively locked while the flag is in vacant position.

A further object of the invention is to provide novel and practical means for permitting the fare drums to be read from the top of the meter. That is to say, it is proposed to provide the fare drums with two series of digits spaced 90° apart, circumferentially of the drum, so that one set of numerals can be readily observed by locking at the face of the 40 meter while the second set of figures can be observed from the top. This arrangement has the advantage of permitting the driver to observe the fare registered on the face of the meter while the meter itself is turned toward the occupant of the vehicle,

A still further object of the invention is to provide a simple and practical differential gearing unit for driving the fare drums at one rate on the initial charge period and at a different rate after the initial charge period has expired. That is to say, in order that a passenger may be given the same value in waiting time for the initial charge fee as he would be given for miles travelled on the initial charge period, it is necessary to provide differential gearing which is automatically operated to drive the fare drums at different rates during the initial charge period and subsequently.

A still further object of the invention is to provide a simple and practical extras drum operating mechanism.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:—

Figure 1 is a front elevation of the meter.

Figure 2 is a rear elevation.

Figure 3 is an enlarged view of the meter mechanism with the front casing and the clock mechanism removed.

Figure 4 is a back view of the meter mechanism with the back plate removed.

Figure 5 is a top plan view of the construction shown in Fig. 4.

Fig. 5^a is a detail view of the locking means for the drum transfer wheels.

Figure 6 is a side elevation looking at the left side of the meter shown in Figure 3.

Figure 7 is a side elevation of the opposite side of the meter looking at the right of the meter shown in Figure 3.

Figure 7^a is a detail view of the lever for locking the fare drums and the star wheel unit.

Figure 8 is a horizontal sectional view more clearly illustrating the location and arrangement of the main driving shaft and the cam shafts,

Figure 8^a is a detail sectional view of the cams on the forward end of one of the cam shaft sections.

Figures 9 and 10 are enlarged detail views taken on the line 9—9 of Figure 3, Figure 9 showing the position of parts with the flag in vacant, and Figure 10 showing the position of parts with the flag in a tariff position.

Figure 11 is an enlarged detail view taken on the line 11—11 of Figure 8, indicating the relative position of parts of the differential rate levers when the flag is up by full lines and indicating by dotted lines the position assumed when the flag is turned to a tariff position.

Figure 12 is a view similar to Figure 11 illustrating the relative position of parts after the initial waiting time period has expired.

Figure 13 is an enlarged detail sectional view taken on the line 13—13 of Figure 3.

Figure 14 is a detail view of the extras drum operating means.

Figure 14^a is an enlarged detail view of the extras actuator shown in Figure 14.

Figure 15 is a view of the back of the meter illustrating the flag locking mechanism, the position of the flag in full line indicating the locked position, and the dotted lines indicating the movement necessary to release the back from its locked position.

Figure 15^a is a detail vertical sectional view of the flag locking instrumentalities and a portion of the back of the meter which supports the flag shaft.

Figures 16 and 17 are views similar to Figure 15 showing the relative position of the parts with the flag in an intermediate and substantially the complete position respectively, the latter indicating the position of parts just before the resetting of the lock.

Figure 16^a is an enlarged detail view of the flag locking means.

Figure 18 is a top plan view of the modification which contemplates inspection openings in the top of the meter casing.

Figure 19 is a flat view of one of the 10¢ drum faces illustrating the spacing of the two sets of numerals to permit inspection of the drum from the face as well as the top of the meter.

Figure 20 is a detail sectional view taken on the line 20—20 of Figure 18.

Figure 21 is a detail bottom plan view of the horizontal frame part showing the shifter lever for throwing out the initial rate lever.

Figure 22 is a detail view illustrating the detector mileage counter operating means.

Figure 22^a is a detail view showing more clearly the detector counter controlling cam.

Figure 23 is a detail view of the extras counter operating means.

Figure 24 is a detail view of the trip counter operating means.

Figure 25 is a detail view of the total miles operating means.

Fig. 26 is a perspective view of the \$1 drum showing its driving side.

Fig. 27 is a perspective view of the \$1 drum showing its transfer side.

Similar reference characters designate corresponding parts throughout the several figures of the drawings.

As shown in Figures 1 and 2, the present taximeter includes in its organization a suitable back plate 1 and a casing or housing 2, having thereon a window 3 for receiving a suitable dial bearing the usual tariff indicia, the back and casing being connected in any suitable manner as by the fastenings 4. The said back plate 1 is also provided with a window 5 for exposing to view a plurality of counter dials which register respectively "Trips," "Extras," "Detector mileage," (meaning distance travelled with the flag in an improper position), "Units" (meaning the number of times that the unit of charge has been registered), "Paid mileage" and "Total mileage".

As will also be observed from Figure 2 the back of the meter is provided with a key 6 for winding the clock 6^a; an extras operating knob K; and the usual flag F for indicating the state of the meter and adapted to be manipulated by the chauffeur according to whether the vehicle is vacant or in use.

Referring first to the meter mechanism in general which is housed within the casing 2 it will be observed from Figure 3 that the said mechanism includes in its organization the opposite frame members or brackets 7 and 8 which are suitably connected in any desired and convenient manner, as for example, by the plate 9 and cross-bar 10 and back plate 11. Mounted in the upper part of the brackets 7 and 8 is a main supporting shaft 12 which is shown in dotted lines in Figures 3 and 5. This shaft carries the main fare drum unit A consisting of the initial or 10¢ drum A¹, the \$1 drum A² and the \$10 drum A³; the extras drum B; the star wheel unit designated generally as C, and also the dual gear unit D of the differential timing unit. All of these various instrumentalities are loose and free on the shaft 12 which simply acts as a carrier or support therefor.

As usual the drums of the main fare unit A are intended to be operated by the movement of the vehicle or by the clock 6^a when the vehicle is hired, and to that end the star wheel unit C may be connected with the road wheel of the vehicle through a novel clutch device C² which is a part of a driving mechanism designated generally as M, or on the other hand the star wheel unit may be driven by the clock work through the medium of the clock driven gear G shown in dotted lines in Figures 3 and 8. The clock mechanism 6^a

is of the usual and ordinary type and lays in front of the gear G, but the same has been partially omitted from the drawing for the purpose of more clearly showing other features which are novel and important.

Driving mechanism for main fare drums

Referring first to the means for driving the fare drums by the movement of the vehicle reference may be made to Figs. 3, 8, 9 and 10.

In Figure 3 the driving spindle 13 may be connected in any suitable manner with the usual reduction gearing and flexible cable 15 to a wheel of the vehicle. This spindle 13 extends upwardly and at its intermediate portion is provided with a ratchet and pawl arrangement 14 for preventing backward movement, while the upper end thereof is 20 provided with a worm 15 adapted to mesh with a worm gear 16 journalled upon a main drive shaft 17 (see Figures 3, 9 and 10). This shaft is journalled in a bracket 18 carried by the frame part 9^a (Fig. 8) and has at one 25 end thereof a pinion 19 adapted to mesh with a larger pinion 20 carried by the frame part 9^a and in turn meshing with a relatively long pinion 21 which is mounted on a fixed spindle 22 extending between the frame parts 9^a 30 and 9^b.

Pivoted to the frame part 9^b as clearly shown in Figures 8, 9 and 10 is the clutch device C² previously referred to, the same comprising a lever 23 pivoted as at 24 to the 35 frame part 9^b and placed under tension by the spring 25 so as to normally have a tendency to move upwardly. This lever 23 is provided with an upward extension 26 (see Figs. 9 and 10) for carrying a clutch gear 40 27 adapted to engage and disengage a gear 28 of the star wheel assembly C, thereby to rotate the latter as will hereinafter more fully appear. For the purpose of controlling the movement of the lever 23 against the 45 tension of the spring 25 the same is provided with a rearwardly extending arm 29 having a hook portion 30 adapted to be controlled by a cam 31 on the cam shaft S. As shown in Figure 9 the cam 31 is in position to 50 maintain the lever 23 depressed and therefore hold the clutch gear 27 out of mesh with the star wheel gear 28. This is the condition of parts when the flag is in vacant. However, when the flag is thrown to tariff 55 position, which is when the flag is in the 90°, 180° or 270° positions, the cam is moved to a position permitting the clutch gear 27 to engage with the star wheel gear 28 and 60 drive the star wheel unit direct from the wheel of the vehicle. The cam 31 will likewise depress the cam 29 and disengage the clutch gear 27 from the star wheel gear when the flag is being rotated from the 270° position to the vacant position so that the fare 65

drums cannot be operated by driving the car when the flag is in vacant position.

Cam shafts

Before proceeding to a description of the star wheel and its means of operation it may be pointed out that the cam shaft is preferably in two sections, namely, the section S previously referred to and clearly shown in Figure 8 and the section S' which is arranged at right angles thereto but connected therewith through the medium of the bevel gears 32. The rear end of the section S' of the cam shaft is provided with a main actuating gear 33 which is clearly shown in Figures 4, 5 and 8, and is intended to be actuated and controlled by the flag operated gear 34 of the flag locking unit shown in Figures 15, 16 and 17. The flag locking mechanism which includes the gear 34 will be herein-after referred to in detail but for the present it will be sufficient to understand that the flag F operates the sections S and S' of the cam shaft through the medium of the intermeshing gears 33 and 34. It will also be observed from Figures 8 and 8^a that the sections of the cam shaft may be provided at convenient points with different cams which will be referred to in connection with parts which they control.

Star wheel unit

The star wheel which constitutes a fare drum actuating unit designated generally as C and mounted on the shaft 12 consists of a five tooth star wheel 35, a driving gear 28 previously referred to and the star wheel unit resetting gear 36. The driving gear 28 is connected to the star wheel by means of a suitable pawl and ratchet clutch 28^a—28^b which is so arranged that when the gears 21 and 28 mesh the star wheel 35 may be driven by the gear 21 of the driving mechanism, but on the other hand when the star wheel 35 is to be driven by the clock work the clutch 28^a—28^b will slip. When this clutch works idly the star wheel 35 is being driven by the time wheels of the differential time unit through the medium of the pawl and ratchet clutch 36^a—36^b carried by the star wheel unit resetting gear 36. (See Fig. 3; also Fig. 13). As will also be observed from Fig. 13 the star wheel unit resetting gear 36 is provided with a stop pin 37 adapted to engage with a stop hook 38 pivoted at 39 to the bar 10. The purpose of this arrangement is to permit the star wheel to always be reset to initial position as will hereinafter more fully appear in connection with the description of the resetting mechanism.

Regardless of how the star wheel unit C is driven, that is, by the clock work 6^a or by the movement of the vehicle, when the flag is in tariff position, the said star wheel operates the 10¢ drum A' of the main fare drum unit 130

A. That is to say, the star wheel unit C is intended to actuate the fare drums either according to distance traveled or waiting time after the cab has been hired and the flag moved from vacant to either the 90°, 180° or 270° position. As this meter is a single tariff meter the fare drums would record the fare when the flag is in the 180° and 270° in the same manner as when the flag is in the 90° position.

Referring to Figures 5, 9 and 10 it will be observed that the 10¢ or units drum A' is fitted with a gear 40 and ten tooth ratchet wheel 41. The gear 40 and ratchet wheel 41 are secured together by suitable fastenings as shown at 41a in Figures 9 and 10, and for the sake of clearness in these figures, the gear 40, which is a part of the resetting mechanism, has been omitted, but can be clearly seen in Figures 3 and 5.

The ratchet wheel 41 is adapted to be advanced one tooth at a time by means of a novel actuating or "drop" lever which is controlled by the star wheel unit C. In Figures 9 and 10 it will be seen that the ratchet wheel 41 is adapted to be engaged by the tooth 42 of the lever arm 43, the said lever arm being pivotally supported on the arm 44 carried by the star wheel actuated or "drop" lever 45 and tensioned by the spring 44a. This star wheel engaging lever is keyed to and carried by a rock shaft 46, and the elongated check pawl 47 loosely mounted on the shaft adjacent the lever 45 is adapted to prevent retrograde movement of the ratchet wheel 41. When the meter is idle and the flag in vacant, the star wheel unit is locked through a part of the resetting mechanism as will hereinafter more fully appear, but the pawl 47 is provided for the purpose of preventing retrograde movement of the ratchet wheel while the meter is in operation. This check pawl 47 is yieldingly maintained in contact with the toothed portion of the ratchet wheel by the spring 48 except when the flag is in vacant position.

Referring further to the star wheel actuated lever 45 it will be observed that the same is provided with an extension 49 adapted to be engaged by a cam 50 on the cam shaft S (Fig. 9) when the flag is in vacant to keep the lever rocked backwardly against the tension of the spring 51, so that the star wheel engaging toe 52 is out of the path of movement of the teeth of the star wheel. As shown in Fig. 10, when the flag is turned to the 90° position the cam 50 disengages the extension 49 and permits the spring 51 to exert its influence to draw the lever 45 toward the star wheel.

However, the lever 45 is only drawn toward the star wheel after the initial charge period has expired to thereby prevent the actuation of the fare drums during the initial charge period; that is, the time period or distance

to which the occupant is entitled for the fare initially appearing on the face of the meter. Therefore, to provide for the receipt by the passenger of the proper value for the initial charge there is provided a restraining lever 53 which is pivoted to the meter frame as indicated at 54 and held under tension by the spring 55. This initial charge lever is provided with two arms 56 and 57, the arm 56 being notched or shouldered as indicated at 56a and adapted to engage with the pin 58 projecting laterally from the side of the lever 45 opposite the arm 44. When the shoulder 56a engages the pin 58 the star wheel actuated lever 45 will be held in the position shown in Figure 9, and it will remain in the position shown in that figure even after the flag is turned to a tariff position for the period of the initial charge which is controlled directly by the star wheel 35 of the star wheel unit C.

As will be observed from Figures 3, 9 and 10 the star wheel 35 is provided with a laterally projecting pin 59 carried by one of the five teeth of the star wheel. Also, as previously indicated the star wheel begins to actuate as soon as the flag is turned into one of the tariff positions, the said star wheel being actuated either by the movement of the vehicle or by the clock. Therefore, during the period required for the pin 59 to move from its original position shown in Figure 9 to a point to lift the restraining lever 53 so as to disengage the shoulder 56a from the pin 58 determines the length or value of the initial charge period. As the star wheel 35 begins to move under the influence of the traveling of the vehicle or clock work, the pin 59 advances toward the lever 53 and strikes the same at the point 60 thereby lifting the lever against the tension of the spring 55 and permitting the toe 52 of the lever 45 to come into contact with the star wheel.

As previously explained the restraining lever has two arms 56 and 57, and as the former which controls the lever 45 has been described reference will now be made to the arm 57 which is shouldered or notched as indicated at 57a (Figs. 9 and 10) thereby to engage with a pin 61 carried by the lever 62 of the differential gearing mechanism which is intended to drive the star wheel unit C slower on "waiting time" during the initial charge period than it is subsequently, that is, when the initial charge period has expired.

Differential time mechanism for operating star wheel unit at slow speed on waiting time during initial charge

Referring to Figures 3, 4, 5, 8, 11 and 12 which show the differential gearing mechanism, it will be seen more clearly from Figure 11, by a comparison with Figure 9 that the arm 57 engages with the laterally projecting pin 61 carried by the subsequent rate lever 62. This lever is provided with a collar 63

journaled upon a shaft 64 and has a pendant arm 65 which is engaged by a relatively strong spring 66 anchored to the frame as at 67. This lever 62 is also provided with a substantially horizontal extension 68 adapted to be engaged by a pin 69 carried by a cam disk 70 mounted on the section S of the cam shaft.

As will also be observed more particularly from Figure 8 the pin 69 is relatively long and is adapted to also engage the arm 71 of an initial rate lever 72 when the flag is in vacant, that is, vertical position. Furthermore, the subsequent and initial rate levers 62 and 72 respectively have mounted on the upper arm portions thereof gears 62^a and 72^a adapted respectively in turn to mesh at different times with the gears 62^b and 72^b of the dual gear unit D loosely journaled upon the shaft 12 and integral with the hub H which carries the ratchet 36^b of the pawl and ratchet device previously referred to.

Both gears 62^a and 72^a are held out of contact with gears 62^b and 72^b when the flag is in vacant, as shown in Figure 11 due to the depressing effect of the pin 69 on both levers 62 and 72. Also, the gears 62^a and 72^a are always in mesh respectively with the relatively large time gear T and the relatively small time gear T' mounted on the time shaft T² which carries the bevelled gear T³ which is driven by the clock work driven gear G previously referred to. Thus, it will be seen that the gears 62^a and 72^a have a relatively planetary movement about the gears T² and T¹ and they are always in mesh therewith, and, because of the relatively large diameter of the time gear T as compared with the diameter of the time gear T¹, the gear 62^a will be driven faster than the gear 72^a.

Therefore, the gear 72^a is the initial rate gear and is utilized to drive the initial charge unit when the cab is waiting on the initial charge period while the gear 62^a is the subsequent rate gear and is utilized to drive the gear 62^b on "waiting time" after the initial charge period has expired. The shifting of the gears 62^a and 72^a into and out of mesh with the gears 72^a and 72^b is entirely automatic, the first step in the series of automatic operations however being controlled by the moving of the flag from vacant into the tariff positions. After the initial charge period has expired however the slow gear train is thrown out and the fast gear train is thrown in automatically.

Referring further to the lever 72 it will be observed that the same is substantially a duplicate of the lever 62 and is provided with a hub or sleeve 73 adapted to be mounted on the shaft 64, on which shaft the lever 62 is also mounted. The lower end of the lever 72 is formed with a pendant extension 75 adapted to be engaged by a relatively weak spring 76 anchored to the frame as at 77.

The pendant portions 65 and 75 of the levers 62 and 72 are guided in suitable slots 78 and 79 in the frame part 9 (see Fig. 3) and cooperate with an automatic shifter-lever 80 which is pivoted to the under face of the frame part 9 as indicated at 90 in such a way that the arm 81 cooperates with the pendant portion 65 of the lever 62 and the arm 82 cooperates with the pendant extension 75 of the lever 72 (see Fig. 21 on sheet with Fig. 12).

When the flag is in vacant, or "flag up" position as shown in Figure 11 the long pin 69 holds both of the levers 62 and 72 in precisely the same position, as shown in full lines, and in that event the shifter lever 80 is not engaged by either of the pendant portions 65 or 75. However, as soon as the flag is turned down, that is, to a quarter turn for example, as indicated by the dotted line position of the pin 69 in Fig. 11, both levers are released by the pin 69 and the springs 66 and 76 exert their influence on the levers. The spring 66 is a strong spring but its influence on the lever 62 will be of no immediate effect when the flag is first turned down because the lever 62 is restrained by the arm 57 of the restraining lever 53.

However, the lever 72 not being under the restraint of the lever 53, its spring 76 which is relatively weak will immediately come into play and move the lever 72 to the dotted line position shown in Figure 11, in which position the lever 72 will remain until the initial charge period has expired.

When the initial charge period has expired and the lever 53 has been elevated by the star wheel and the arm 57 likewise lifted to disengage the shoulder 57^a from the pin 61, the lever 62 will be immediately actuated through the influence of the strong spring 66. The effect of the actuation of the lever 62 by the strong spring 66 is to pull the pendant portion 65 of the lever 62 toward the arm 81 of the shifter lever 80 and thus cause the arm 82 of the shifter lever to throw the pendant portion 75 of the lever 72 outwardly and consequently rock the upper end of the lever 72 inwardly as shown in Figure 12 thereby throwing the gear 72^a out of mesh with the gear 72^b and disconnecting the slow gear train from the initial charge unit C and simultaneously throwing in the fast gear train which includes the gear T and gear 62^a which drives the gear 62^b.

By way of briefly stating the action of the differential time gearing it may be pointed out that when the flag is in vacant both the levers 62 and 72 are held in such a position that the gears 62^a and 72^a are entirely free from the gears 62^b and 72^b which drive the star wheel 35. When the flag is turned to the tariff positions the levers 62 and 72 are released or unlocked by the cam shaft S but the lever 62 remains restrained in its orig-

inal position while the lever 72 moves under the influence of the weak spring 76 to cause the gears 72^a and 72^b to mesh and thus drive the star wheel 35 at a slow speed.

When the initial charge period has expired either due to distance traveled or waiting time and the restraining lever 53 is shifted to disengage the shoulder 57^a from the pin 61, the lever 62 is operated by the strong 10 spring 66 to simultaneously cause its gear 62^a to mesh with the gear 62^b and also move the shifter lever 80 to counteract the influence of the weak spring 76 and disengage the gears 72^a and 72^b. When the meter is reset the 15 pin 69 under the control of the cam shaft S rocks both levers 62 and 72 to cause their gears to disengage from the gears 62^b and 72^b.

Detector counter

20 It has been found desirable to provide a check on the driver running with his flag in a position between zero and 90° or between 270° and 360°. Between zero and 90° the various instrumentalities of the meter are 25 thrown into operative position and most of them become completely engaged when the flag reaches the full 60° point. Likewise between the 270° position and the 360° position the various parts of the meter are going 30 through the resetting operation and if the meter is operated while the flag is between these two positions incorrect results are obtained.

Therefore, to provide a record when the 35 chauffeur drives his cab with the flag in a prohibited position the detector counter designated generally as 91 is provided. This detector counter is shown in Figures 1, 3, 4, 7 and 22 and it may be of the conventional ratchet-operated type. By reference to Figure 7 it will be observed that the ratchet wheel 92 of the counter is provided with the usual check pawl 93 and the operating pawl 94 which is yieldingly pivoted as at 95 to an 40 actuating arm 96. This actuating arm 96 is pivoted on a pin 95' and extends upwardly and is provided with an offset end 97 (Fig. 22) adapted to be engaged by laterally projecting pins 98 carried by a clutch disk 99 45 which is slidably mounted upon a counter shaft 100 which is driven by the movement of the wheel of the vehicle directly from the main drive shaft 17 through the medium of the gear 101 and intermediate gear 102 (Fig. 50 55 6) which in turn meshes with a gear 103 directly on the main shaft 17. Therefore, the shaft 100 moves continuously when the vehicle is in motion but due to the fact that the clutch disk 99 is loosely mounted thereon, the 60 clutch disk will be idle except when the flag is in an unauthorized position.

As will be seen from Figure 3 the clutch disk 99 is provided with a hub 99^a having a clutch face for engaging with a mating clutch 65 face on the hub of the continuously driven

gear 101. When the flag is in vacant or tariff positions the clutch disk 99 is held in the position shown in Figure 3 wherein the clutch faces of the hubs 99^a and 101^a are disengaged. The clutch disk 99 is controlled by the clutch lever 104 which is pivoted on the shaft 105 which also carries additional levers as will presently appear, and the end 106 of the lever 104 is adapted to be controlled by cam 107 mounted on the cam shaft S'. The said cam 107 is provided with cut away portions 108 and 109 corresponding to the prohibited positions of the flag in its cycle of movement as shown in Figures 3 and 22^a wherein it includes the projection 110 having on each side 80 thereof the recesses 108 and 109 previously referred to and the smooth periphery 111. When the flag is in vacant position the projection 110 engages with the end 106 of the lever 104 and maintains the clutch faces of 85 the hubs 99^a and 101^a disengaged thereby keeping disk 99 disconnected from disk 101. However, as soon as the flag is moved toward the 90° position the end 106 of the lever 104 drops into the recess 108 and causes the disk 99 to be connected with the gear 101 so that if the cab is traveling and the flag remains in any position between zero and 90° the mileage accumulated by such traveling will be registered on the dials of the counter 91.

When the flag is in substantially any position between 90° and 270° the end 106 of the lever 104 will ride on the periphery 111 of the cam 107 and thereby hold the disk 99 out of engagement with the gear 101. However, between substantially the 270° position of the flag and the 360° position the end 106 of the lever 104 will drop into the recess 109 and again cause the disk 99 to be connected with the gear 101 so that if the cab travels with the flag in that position, the mileage thus accumulated will also be registered on the dials of the counter 91 until the flag is moved back to its vertical or vacant position when the end 106 of the lever 104 will rest on the projection 110.

Therefore, it may be seen that mileage traveled with the flag in an unauthorized position will be readily registered on the counter 91 and the chauffeur of the cab can be held to account for the illegal operation of his cab.

Extras mechanism and counter therefor

The drum 112 of the extras registering mechanism B is intended to be operated by the chauffeur to indicate, in the usual manner, the items of extra fare to be exacted from the passenger and is operated by the knob K on the back of the meter. As will be observed from Figure 14 the said drum 112 is mounted upon the supporting shaft 12 to turn freely thereon, and is placed under tension of a coil spring 113 whose ends are respectively fitted to the shaft and the drum 120 125 130

thereby to tend to maintain the projection 114 on the inside face of the drum in engagement with a stop bracket 115 carried by the bar 10. (See Fig. 3.) Also, the drum is provided with a ratchet 116 which is adapted to be engaged by a check pawl 117 pivotally supported on a stud 118 and tensioned by the spring 119.

The stud 118 which carries the check pawl 117 also carries a main operating lever 120. This lever is provided with an offset ear 121 for carrying a pivoted advancing pawl 122 whose free end 123 is adapted to engage with the ratchet 116 to advance the drum. The lower ends 117^a of lever 117 and 124 of the lever 120 are adapted to be engaged by a pin 125 carried by a cam disk 126 on the cam shaft S so that when the flag of the meter is in the vertical or vacant position the pin 125 will engage with the nose formed on the end of 124 and prevent operation of the lever 120, and also pawl 117 out of the ratchet 116. However, when the flag is returned to a tariff position the pin 125 moves away from the end 124 and permits the extras operating mechanism to be released for operating the drum 112 and also permits pawl 117 to engage the teeth of ratchet 116.

The body of the lever 120 below the ear 121 is provided with an offset operating arm 127 which is provided with a substantially horizontal foot 128 to which is connected a tensioning spring 129 for the purpose of maintaining the lever 120 in position to cause the pawl 122 to be clear of the ratchet 116.

As will also be observed from Figures 14 and 14^a the foot 128 is adapted to be engaged by the arm 130 of a pivoted actuating lever 131 which is directly under control of the knob K on the outside of the meter. That is to say, the knob K and the lever 131 are connected in any suitable manner, as for example, by the fastening 132 so that movement of the knob K in the direction of the arrow in Figure 14^a will cause the arm 130 to move upwardly and lift the foot 128 thereby causing the pawl 122 to dip down into the ratchet 116 and move the drum forward one tooth. The drum will then be held locked by the free end of the pawl 117.

The lever 131 is also provided at the end opposite the arm 130 with an overhanging pressure finger 133 which is adapted to engage with the counter actuating arm 134 which is intended to transmit motion to the extras counter 135 (see Figs. 3 and 23). The said arm 134 is pivotally mounted on a supporting shaft 135^a and the lower arm 136 thereof (see Figs. 4 and 7) carries a counter operating pawl 137 for operating the ratchet 138 of the counter 135. Thus, each time that the knob K is reciprocated to register a unit of extras on the face of the drum 112, the counter 135 will register an additional unit of extras. The extras

drum is reset by spring 113 when pawl 117 is lifted out of ratchet 116 as indicated, and when flag is returned to vacant.

Operation of miscellaneous counters

Referring further to the group of counters for registering the various totals accumulated by the device it will be observed that immediately above the extras counter 135 above referred to, that there is a so-called "trip" counter 139 (see Figs. 3, 4 and 7 and 24). This counter is operated by a lever 140 whose upper end is operated by a cam 141 on the cam shaft S and whose lower end 142 is of angular formation carrying therewith at its extremity a pivoted spring tensioned pawl 143 for engaging and advancing the ratchet 144 of the counter 139. Each time that the cam shaft S makes a complete cycle the lever 140 is rocked by the cam 141 and the complete cycle of the flag shaft is registered on the dials of the counter 139.

The total miles counter 145 includes a ratchet 146 (see Figs. 3, 6 and 25) which is operated by a spring tensioned pawl 147 carried by a lever 148 whose upper end is pivoted as at 149 to a suitable frame part and is provided with the offset arm 150 adapted to be engaged by the pins 151 carried by the gear 101 which is driven from the main shaft 17. Obviously, with this arrangement, since the gear 101 is continuously driven by the movement of the vehicle the rotation of the pins 151 will rock the arm 148 and thus cause the ratchet 146 to register the total miles on the face of the dials of the counter 145.

The paid mileage counter is designated as 152 and is located above the total mileage counter 145. This counter includes ratchet wheel 153 adapted to be operated by a pawl 154 pivotally carried as at 155 by the lever 156 which is tensioned by the spring 157 and pivoted at its upper end as indicated at 158 (see Fig. 6). The lever 157 also has an offset arm 159 adapted to be engaged by pins 160 carried by the disk 161 of a clutch sleeve 162 (Fig. 3) which is freely slidable on the counter shaft 100 and carries therewith a clutch collar 163 adapted to be engaged by the shifter lever 164. The clutch sleeve 162 is provided with a clutch face 165 for engaging with a clutch face 166 on the hub of the continuously driven gear 101 which is operated from the main shaft 17, and when the cab is hired and earning a fare it is intended to shift the clutch sleeve 162 so that the clutch faces 165 and 166 will engage. Such shifting is accomplished by the lever 164 which is pivotally supported as at 167 and has an upwardly extending arm 168 whose end 169 (see Fig. 8^a) is adapted to be engaged by the pin 170 projecting from the side of the detector operating cam 107. As the clutch faces 165 and 166 are intended to always engage when the flag is in the tariff positions it is only necessary to provide the pin 170 for

holding the clutch open when the flag is in the vertical or vacant position. As soon as the flag is moved from the vertical position the paid miles clutch device immediately goes into operation to register the paid miles on the register or counter 152. For the purpose of preventing retrograde movement of the sleeve 162, the edge of the disk 161 may be made in the form of a ratchet edge to engage with a spring detent 161^a.

The "units" counter 171 (see Figs. 4 and 6) is mounted above the "paid miles" counter 152 and includes a ratchet wheel 172 (see Fig. 6) adapted to be actuated by the end 173 of a relatively long arm 174 which is pivotally carried as at 175 by a lever 176 mounted on the rock shaft 46 which carries the so-called drop or star wheel actuated lever 45. The purpose of this counter 171 is to register each actuation of the lever 45, and therefore each time the nose 52 of the lever 45 is actuated by one of the teeth of the star wheel 35, the shaft 46 which carries the lever 45 will be rocked to thus reciprocate the arm 174 and actuate the ratchet 172. The arm 174 is tensioned by the spring 174^a and is also guided against the headed screw 174^b.

Accordingly, it will be understood that the "units" register is intended to keep a record of each time that the lever 45 is actuated for the purpose of checking up on the number of units which have been put on the fare drums. These units may be dimes, centimes or any other unit of value according to the money values where the meter is used.

Flag locking mechanism

The back plate 1 of the meter carries there-with the flag F as previously indicated and it is the purpose of the present invention to provide means for locking the flag in vacant position temporarily and yet permitting the same to be readily released without the necessity of the operator using a separate manually manipulated knob or key. In other words it is the purpose of the present invention to provide a flag that becomes automatically locked at the end of each cycle, and can be automatically released by a partial reverse movement.

Accordingly, as will be observed from Figures 15, 15^a, 16, 16^a and 17, the flag F is provided with a shaft 180 which is journaled in the back of the meter as indicated at 181 and has fitted thereto a series of devices for controlling the meter mechanism and also setting the flag at the different positions of its cycle. From Figure 15^a it will be seen that the shaft 180 is provided with a disk 182 portions of which are provided with ratchet teeth to be engaged by a spring pressed pawl 183 (Figs. 15, 16 and 17) thereby to compel movement of the flag in one direction only during the movement from zero to 90° and from 270° to 360°. Next to the disk 182 there is provided

a position determining cam 184 which preferably includes four equally spaced notches or recesses adapted to receive a roller 185 carried by an arm 186 whose free end is engaged by a spring 187. The purpose of the cam 184 is to cause the flag to stop temporarily at each 90° of movement in accordance with the well known custom.

Adjoining the cam 184 is a novel locking member 188 while at the end of the shaft 180 the gear 34 previously referred to is secured by a set screw 34^a or its equivalent.

The locking member 188 and the parts which cooperate therewith constitute one of the novel and distinctive features of the present invention. As shown the member 188 is in the form of a circular disk having an offset substantially T-shaped locking and releasing head or lug 189. The special formation of the lug 189 provides a keeper socket 190 adapted to receive a detent 191 which is pivotally supported on the back 1 as indicated at 192 and tensioned by the spring 193. When the flag is in vacant position, that is, the full line position shown in Figure 15 the detent 191 will prevent rotation of the flag F in the direction of the heavy arrow and in order to release the flag from the locking effect of the detent 191 it is necessary to move the same backwardly to the dotted line position shown in Figure 15 whereupon the keeper portion of the head 189 will be moved clear of the free end of 191 to permit the spring 193 to pull the detent to the dotted line position shown in Figure 15 or the full line position shown in Figure 16. The flag may then move onward in its cycle. When the flag is turned backwardly in the direction of the dotted arrow in Figure 15 to permit the head 189^a to clear the detent 191, the portion 189^b of the head 189 is thrust into the socket of the hook 194 formed on the trigger lever 195 thereby preventing too far backward movement of the flag.

The trigger lever 195 is pivotally secured to the back as indicated at 196 and is provided with an offset resetting foot 197 for again placing the detent 191 in obstructing relation to the locking projection 189. That is to say, as the flag moves toward the end of its cycle, and reaches the position shown in Figure 17 the portion 189^a of the locking projection 189 will engage the rounded surface of the hook 194 and thus rock the trigger 195 so that the foot 197 will engage the detent 191 and place it directly in position to fit into the socket 190 formed between the portion 189 of the locking projection and the shank thereof. The detent 191 will remain in the socket 190 and maintain the flag F locked against further progressive movement through a new cycle until it has again been moved backwardly a sufficient distance to permit the spring 193 to shift the detent 191 out of the socket.

Therefore, an effective automatic lock for

the flag is provided, the same being unlocked or released by a simple partial reverse movement of the flag, as previously indicated.

Resetting mechanism

5 The resetting mechanism for returning to zero the main fare drums of the unit A as well as the drum 112 of the extras unit B is clearly shown in Figures 5 and 7 and also 10 partly shown in Figures 3, 13 and 14.

Referring first to the fare drums A¹, A² and A³ of the main fare registering unit it will be observed that these drums are of the type wherein the units drum is actuated directly by the star wheel 85, lever 45 and arm 43 and the \$1 and \$10 drums A² and A³ are actuated in turn as required through the carry-over mechanism which includes the transfer pinions 200 (see Figs. 4, 5 and 5^a) carried by a bracket 201 mounted on a rock shaft 202 and maintained in operative relation to the drums when the flag is in any of the tariff positions, by a spring 203 which engages with the horizontal arm of the bracket 25 201.

During the resetting operation an arm 204 on the rock shaft 202 is intended to be engaged by a projection 205 carried by a cam 206 mounted on the cam shaft S thereby to 30 temporarily hold the transfer pinions 200 in the full line position shown in Figure 5^a and out of engagement with the fare drums thereby permitting the fare drums to be reset. When the transfer gears 200 are held 35 out of engagement with the fare drums during the resetting operation it is pointed out that the same are held in precisely the position which they left the fare drums due to the fact that the hubs of the transfer pinions 40 are made square as indicated at 207 so that when the pinions are rocked rearwardly they will engage the springs 208 which will hold them against movement through jarring of the vehicle and permit them to re-engage with 45 the fare drums properly when the flag completes its cycle. For the purpose of properly adjusting the tension of the spring 203 and also adjusting the degree of rocking movement of the bracket 201 an adjustable stop 50 209 may be employed. This stop is preferably in the form of a bolt or screw whose threaded shank portion engages with the support 201 and receives a crown nut 211, one of the fingers of which also serve as a support for the spring 203 (see Figs. 4, 5 and 5^a).

The units drum A¹ has fitted thereto, as previously described, a resetting gear 40 adapted to engage with a gear 212 carried by a resetting shaft 213 which is journaled in 5 the opposite frame ends 7 and 8 and projects through the frame 8 as indicated in Figures 5 and 7 where it is provided with a pinion 214 and also with a locking cam 215 having a shoulder 215^a. The pinion 214 meshes with 10 an idler gear 216 pivotally mounted on the

outside of the frame 8 and carries therewith a pinion 217 adapted to mesh with a resetting gear 218 which in turn is equipped with a resetting ratchet 219 adapted to be engaged by the toothed portion 220 of a resetting pawl 221. The said pawl 221 is pivotally carried as at 222 by a main resetting lever 223 which is pivotally supported at its lower end as indicated at 224 to the outside face of the frame 8. For the purpose of tensioning the pawl 221 a spring 221^a is utilized, and likewise for the purpose of tensioning the lever 223 a spring 225 is attached to its upper end.

As shown in Figure 7 the lever 223 is provided with a finger 226 which is adapted to cooperate with a resetting cam 227 mounted on the end of the cam shaft S which projects beyond the side frame 8. This cam is provided with a notch 228 which is adapted to receive the finger 226 when the flag is traveling through the resetting part of its cycle and also to receive said finger when the flag is in vacant as shown in Figure 7. When the flag is turned to the 90° position the finger 226 is lifted out onto the periphery 229 of the cam thereby rocking the lever 223 rearwardly so as to disengage the initial one of the teeth 220 on the pawl 221 from the ratchet 219 thereby to permit the ratchet 219 to rotate freely when the fare drum A' rotates. It will therefore be understood that the finger 226 rides on the periphery 229 of the cam 227 throughout the tariff positions of the flag.

As will also be seen from Figure 7 the cam shaft S is fitted with a cam 230 between the cam 227 and the face of the side frame 8. This cam is in the form of a circular disk whose periphery is notched as indicated at 231 thereby to receive the tail portion 232 of a bell crank shaped rocking lever 233 which is pivoted to the frame 8 as indicated at 234 and has an upwardly extending arm 235 provided with an offset portion 236 for engaging with the shoulder of the locking cam 215^a, (see Figures 7 and 7^a). The lever 233 also has a horizontal arm 237 which is likewise provided with an offset portion 238 for engaging with the shoulder 239 of a locking cam 240 carried by the star wheel resetting shaft 241 (see Figs. 3, 7 and 13). The purpose of the lever 233 is therefore to lock the resetting shaft 213 for the units fare drum A' and also lock the resetting shaft 241 of the star wheel resetting mechanism while the flag is in vacant position. As soon as the flag is turned to a tariff position the tail 232 of the lever 233 is lifted out onto the periphery of the cam 230 thereby rocking the lever 233 backwardly on its pivot toward the rear of the frame member 8, against the tension of the spring 233^a to thereby remove the projections 236 and 238 out of the path of the shoulders 215^a and 239. When the lever 233 is thus rocked backwardly the star 100 105 110 115 120 125 130

wheel unit C is free to operate and likewise the initial fare drum A' of the main fare register unit A is also released.

Before proceeding to a further description 5 of the star-wheel resetting means it may be pointed out that as the flag completes its cycle to accomplish resetting, toward the end thereof, the main resetting lever 223 is drawn forwardly under the influence of the spring 10 225 when the arm 226 registers with the notch 228 thereby pushing the pawl 221 forwardly so that the teeth 220 thereof propel the ratchet 219 which in turn propels the resetting gear train 218, 217, 216 and 214, shaft 15 213 and resetting gear 212. Also, the locking lever 233 is again placed in position to engage the shoulders 215^a and 239 of the locking cams previously described.

The 10¢ drum A¹, as shown in Fig. 27, is 20 provided with a Geneva tooth 300 which engages with its transfer pinion 200 each time the 10¢ drum A¹ makes a revolution, thereby rotating its transfer pinion 200 one tooth and the \$1 drum A² through the gear 301 a 25 distance sufficient to bring the next numeral thereon into view. The 10¢ drum A¹ is also provided with a lug 302 and the \$1 drum A² is provided with a pivoted catch 303 whose end 304 is normally pressed against the hub 305 of the \$1 drum by means of a spring 306. The other end of the catch 303 is provided with an intended flaring end 307. As the units drum is rotated when being reset the lug 302 engages the flaring end 307 of the 35 catch 303 and thereby picks up the \$1 drum and rotates it until the pin 308 is engaged by a pivoted hook 309 similar to the stop hook 38 shown in Fig. 13. The \$10 drum is provided with a pin 310 which engages a fixed stop 40 311 carried by the frame of the machine when the \$10 drum has been returned by its spring 312 to zero position as is clearly shown in Fig. 6. All of the fare drums and the star wheel unit are therefore returned to their 45 initial position when being reset, and they are locked against retrograde movement, the 10¢ drum being locked in this position by the lug 302 engaging the end 307 of the catch 303 and the pivoted hook 309 by engaging the 50 pin 308 locks the \$1 drum against retrograde movement while the stop hook 38 by engaging the stop pin 37 locks the star wheel unit C against retrograde movement. Furthermore, all of these members are locked against 55 movement in the opposite direction by means of the shoulder 215^a engaging the offset 236 of the arm 235 as is shown in Fig. 7.

Star wheel unit resetting means

60 The resetting shaft 241 previously referred to carries therewith a pinion 242 between the cam 240 and the face of the side frame 8 (see Fig. 7). The pinion 242 meshes with a resetting gear 243 which carries therewith 65 a ratchet 244 adapted to be engaged by a

resetting pawl 245 carried by a lever 246 and tensioned by a spring 247. The lever 246 is itself under the tension of the spring 248 and is pivoted as at 249 to the face of the side frame 8. The upwardly extending 70 arm 250 of the lever 246 is provided with the lug 251 adapted to be engaged by a cam 252 mounted on the cam shaft S at the outside of the cam 227, therefore appearing in full lines in Fig. 7. This cam 252 is in the 75 form of a circular disk having a notch 253 adapted to receive the lug 251 at the beginning of the resetting movement of the flag, thereby to permit the spring 248 to lift the lever 246 and cause the pawl 245 to rotate 80 the ratchet 244. The lug 251 remains in the notch 253 after resetting while the flag is in vacant, but as soon as the flag is turned to the 90° position the lug 251 is lifted out of the periphery of the cam thereby lowering 85 the lever 246 and disengaging pawl 245 from the ratchet 244 to permit the free rotation of the star wheel unit.

As will be seen from Figure 3 the resetting shaft 241 carries therewith a resetting gear 241^a (see Fig. 13) which is adapted to mesh with the resetting gear 36 of the star wheel unit, and therefore when the clutch gear 27 (Fig. 9) is disengaged from the driving gear 28 of the star wheel unit, and likewise when the time gears 62^a and 72^a are disengaged from the gears 62^b and 72^b (Fig. 11), the upward movement of the pawl 245 will cause the ratchet 244 to rotate and thereby transmit rotational movement to the shaft 100 241 through the intermeshing pinion and gear 242—243.

Top inspection of fare drums

Another novel and distinctive feature of 105 the present invention resides in the modification shown in Figs. 18, 19 and 20 wherein the casing 2 is provided in its top wall with windows 3^a and 3^b in addition to the main window 3 in the front wall of the casing 110 which permits the exhibition of the fare drums when the meter is earning a fare.

The purpose of the windows 3^a and 3^b is to permit the driver of the cab to always observe the amount of the fare registered 115 on the face of the meter without the necessity of dismounting from the cab to read the face of the meter or without swinging the meter from its normal position which permits it to be viewed from the interior of the cab.

To permit of the carrying out of this feature the fare drums A⁵ as well as the extras drum B⁵ are provided with two series of numerals, namely, the series N which constitutes the passengers fare indication and a separate series of smaller numerals N' arranged along either margin of the drum as shown in Figure 19. It will be observed however, that the numerals of the series N 120

and N' are arranged in relatively staggered relation and the smaller numerals of the series N' are spaced 90° from the large numerals of the series N so that when the large 5 numerals are visible from the face of the meter through the window 3 the corresponding small numeral will be visible through the opening 3^a in the masks of the window 3^a at the top of the meter.

10 In Fig. 19 one of the numeral strips of the fare drums is shown flat to better illustrate the spacing of the numerals as above referred to. It will of course be understood that the small numerals constituting the series N' may be arranged at either one side or the other of the large numerals of the series N according to whether the drum to which the numerals are applied is a "units" drum or a "tens" of units drum. In 15 20 the case of the extras drum B^5 wherein a single drum is employed, the same relative spacing of large numerals in the series N and N' is observed.

Figure 20 of the drawings clearly illustrates the relative position of the fare drums to the windows 3 and 3^a and 3 and 3^b to permit of the dual inspection of the fare drums in accordance with the plan proposed.

Miscellaneous operations

30 Figs. 3, 8 and 8^a of the drawings illustrate a cam 260 mounted on the cam shaft S' for actuating an angular lever 261 which is known as the clock stop. The lower arm of this lever carries a spring 262 adapted to engage the balance wheel of the clock escapement when the flag is in vacant position thereby to stop the clock. When the flag is turned into a tariff position the cam 260 35 40 pushes the nose of the lever 261 out onto this periphery and lifts the lower arm of the lever to release the clock for operation.

Also, Figures 3 and 8^a of the drawings illustrate a shutter operating cam 263 which is adapted to operate an angular shutter lifting lever 264. This lever 264 is provided with a lifting foot 265 adapted to cooperate with a suitable post (not shown) carried by the shutter 266 which hides the face of the fare 45 50 55 drums when the flag is in vacant and bears the indicia "Not registering" as per Figure 1 of the drawings. This feature is common in taximeters and it has been set forth here merely to explain the presence and function 60 65 of the lever 264.

General operation

When the flag is in vacant position as shown in Figures 1, 2 and 3 the main face drums A^1 , A^2 and A^3 are locked against movement 60 65 70 in a forward direction due to the engagement of the projection 236 with the shoulder 215^a on the cam 215 which is carried by the shaft 213. Likewise the star wheel unit C is locked 75 against forward movement due to the engage-

ment of the projection 238 of the lever 238 (Fig. 7) with the shoulder 239 of the locking cam 240 on the shaft 241.

Also, the clutch gear 27 is held out of engagement with the gear 28 which drives the star wheel as shown in Figure 9, and the clock-work driven wheels 62^a and 72^a are held out of engagement with the gears 62^b and 72^b respectively of the dual gear unit mounted on the shaft 12 (Fig. 11).

The flag F is also locked due to the engagement of the detent 191 in the socket 190 as shown in Fig. 15, and when it is desired to set the meter in operation the flag F is given the partial movement shown in dotted lines in Figure 15 to automatically release the flag lock. The flag may then be moved toward the 90° position where it is temporarily arrested due to the engagement of the roller 185 in one of the notches of the member 184, but before reaching the 90° position the cam 107 on the flag shaft S^1 (Figs. 3 and 8) rocks the lever 104 to throw the detector clutch disk 99 into operative engagement with the wheel-driven gear 101 so that if the cab 90 should travel before the flag reaches the 90° position the detector counter 91 will register the illegal mileage.

When the flag reaches the 90° position the meter is fully set in its operative position, and the turning of the flag to the 180° or the 270° position will have no further effect upon the control of the meter mechanism because of the fact that the present construction is what is termed a single tariff meter. Therefore, when the flag is in either the 90° , 180° or 270° position the clutch gear 27 (Fig. 10) will be engaged with the star wheel gear 28 so that movement of the vehicle will cause the star wheel 35 to rotate.

The rotation of the star wheel 35 may therefore be accomplished by the traveling of the vehicle or it may be effected by the clockwork through the throwing into mesh of the slow gear train T' , 72^a , 72^b in event that the cab stands still or "waits" immediately after being hired.

Therefore, the setting of the flag F in a tariff position immediately connects the star wheel 35 with either a driven part of the vehicle or the clock.

For a predetermined time period, or predetermined distance to be traveled for the amount of the initial charge registered on the face of the meter, the restraining lever 53 functions to hold the star wheel actuated lever 45 out of contact with the star wheel (Fig. 9), and to also hold the fast gear train (T , 62^a and 62^b) out of mesh and therefore inoperative as shown in Figure 11.

However, just as soon as the initial charge period has been used up either in distance traveled or time waited the lug 59 of the star wheel 35 shifts the restraining lever 53 to move the arms 56 and 57 thereof respectively

out of restraining engagement with the lever 45 and the lever 62. The lever 62 (Figure 11) immediately throws the lever 72 to an inoperative position (Fig. 12) so that the continued operation of the vehicle will permit the meter to register on distance traveled or time waited.

Some cities require that the passenger shall pay a higher rate for an initial unit of distance than he is charged for subsequent like units but that the charges for waiting shall be uniform. If, for instance, the charge is 20 cents for the first one-fourth mile and 10 cents for succeeding one-fourth miles while the waiting charge is \$1.50 per hour, a taximeter of the kind disclosed will give the correct charge for distance traveled without the necessity of having two trains of gears from the shaft T^2 , but on the other hand, if the vehicle be hired and then kept in waiting, the two trains of gears are necessary, for otherwise the passenger would be charged 5 cents for each of the first four minutes and two and one-half cents for each succeeding minute, which is contrary to the law, and furthermore, the charge for the first hour would be \$1.60, and for succeeding hours would be \$1.50, whereas the city regulations require that the charge shall be only \$1.50 per hour.

However, by providing a slow gear train T^1 , 72^a and 72^b which drives at one-half the speed of the fast gear train T , 62^a and 62^b, the star wheel 35 is driven at one-half its speed for the initial time period and at its regular speed thereafter so that the passenger is charged two and one-half cents per minute waiting time regardless of whether the taxicab is kept in waiting when first hired or at a later period of time.

When the flag has been turned to the tariff positions the extras mechanism is automatically unlocked by the shifting of the projection 125 away from the end 124 of the extras operating lever 120 and away from the end 17^a of the lever 117 shown in Figure 14. The chauffeur may then register the extras on the face of the meter and the extras registered will also be accumulated on the extras counter 135 as shown in Figures 3 and 4.

After the passenger has finished his trip the flag is moved from its running position through the last quarter of its cycle, namely, from 270° to 360°. This portion of the cycle of the flag is the resetting cycle and after the flag has moved slightly past the 270° position the pawl 183 (Fig. 17) engages with the teeth of the ratchet 182 to prevent the backward movement of the flag. As the flag proceeds further toward the 360° position the cam 31 on the cam shafts S engages the nose 30 of the clutch lever 29 and disengages the clutch gear 27 from the gear 28 of the star wheel assembly C while at the same time the cam 50 of the cam shaft S engages the tail 49 of the lever 45 and draws it backwardly

to its inoperative position as shown in Figure 9. At the same time the pin 69 on the cam 70 of the cam shaft S draws both levers 62 and 72 of the differential time unit backwardly to the full line position shown in Figure 11 thereby to disconnect the gears 62^a and 72^a and 62^b and 72^b. As the levers 45, 62 and 72 assume their normal positions the restraining lever 53 drops to cause the arms 56 and 57 thereof to respectively engage the pins 58 and 61 on the levers 45 and 62 (Fig. 9).

Simultaneously with the disconnecting of the above instrumentalities the main fare drums A', A² and A³ are reset due to the forward movement of the pawl 221 carried by the lever 223 (Fig. 7). The forward movement of the pawl 221 acting upon the ratchet wheel 219 imparts a rotational movement to the gear train 218, 217, 216, and 214 to thus cause the shaft 213 to reset the units drum A' and the latter will in turn pull back the drums A² and A³ to their normal position. To permit the resetting of the drums A', A² and A³ the transfer wheels 200 are maintained temporarily withdrawn from the gears of the fare drums as shown in Figure 5^a due to the engagement of the lug 205 with the lever member 204.

The extras drum 112 of the extra unit B is also released to return to its normal position against the stop 115 under the influence of the spring 113 when the cam 126 on the cam shaft S rocks the lever 120 rearwardly as shown in Figure 14 thereby to also lock the same until the flag is again moved to start a new cycle.

The star wheel unit C is reset simultaneously with the fare drums A', A² and A³ due to the engagement of the pawl 245 with the ratchet 244 on the gear 243, the latter propelling the resetting shaft 241 through the pinion 240. The upward movement of the lever 246 under the influence of the spring 248 carries the pawl 245 upwardly and imparts sufficient rotational movement to the gear 243 to effect the resetting of the star wheel unit, thereby carrying the star wheel unit back to the position shown in Figure 13 where the gear 36 thereof has the stop 37 engaging with the hook 38.

Immediately upon the completion of the resetting movement the shafts 213 and 241 become positively locked by the engagement of the projections 236 and 238 of the lever 233 with the shoulders 215^a and 239 of the locking cams 215 and 240 respectively. This lock which is under the control of the flag positively prevents accidental or unauthorized movement of the fare drums or the star wheel unit although both of these parts are loosely mounted on the shaft 12. The fare drums have their own initial abutment stops and the star wheel unit has the stop 37-38 shown in Figure 13 which limit backward move-

ment, and the lever 233 and the cams 215 and 240 prevent forward movement of the fare drums and star wheel unit so that both are effectively locked against movement in any direction when the flag is in vacant position.

As soon as the flag reaches its 360° position it is immediately arrested and locked against further continuous movement by the 10 detent 191 and the locking head 189 as shown in Figure 15 and fully described in connection with Figures 15, 16, 16^a and 17.

It will of course be understood that during the complete cycle of the flag the paid mileage counter 152 is thrown into operation to register the paid miles, also the units counter 171 is rendered operative to count the number of times that the lever 45 is operated while the detector mileage counter 91, extras counter 135 and the trips counter 139 are all rendered operative to accumulate the intended totals in the manner described in connection with each unit.

The total mileage counter 145 is of course always operative regardless of whether the vehicle is earning a fare or cruising for a fare thereby to enable the owner of the cab to accurately check up the total miles traveled with paid mileage, trips, etc.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A taximeter including a flag, means for locking the flag at the end of each cycle, including a disc provided with a cam and a keeper socket, a spring tensioned detent and a trigger member adapted to be engaged by said cam and press said detent into position to enter the socket.

2. A taximeter including a flag, means for locking the flag at the end of each cycle, including a T shaped cam having a socket, a spring tensioned dentent normally urged away from said socket, and a trigger member adapted to be engaged by said cam and to press said detent into position to enter the socket.

3. A taximeter including a flag, means for locking the flag at the end of each cycle, including a T shaped cam provided with two sockets and adapted to be rotated by said flag, a dentent adapted to be engaged by one of said sockets, means tending to pull said dentent away from its socket, a trigger member provided with a hook, a socket being formed between said hook and the trigger member, said cam engaging said hook during a portion of the rotation of said cam and moving

said trigger member so as to force said dentent into its socket, and means whereby said trigger member is moved so that said hook will engage other of said sockets as soon as the cam passes beyond said hook.

4. A compact assembly for taximeters including in combination with the distance and time elements, of a pair of flag operated counter controlling cam shaft sections disposed in right angular relation.

5. A compact assembly for taximeters including in combination with the distance and time elements, of a pair of flag operated counter controlling cam shaft sections disposed in right angular relation, said cam shaft sections being geared together for movement in unison.

6. A compact assembly for taximeters including a fare drum actuating unit, a vehicle actuated shaft having a clutch connection with said fare drum actuating unit, a time shaft also having a clutch connection with the fare drum operating unit, and a pair of flag operated cam shaft sections geared for movement in unison.

7. A compact assembly for taximeters including a wheel-operated shaft, a time operated shaft, a star wheel unit for actuating the fare drums having separate automatic clutch connections respectively with the wheel operated and time shafts, and a pair of right angularly disposed cam shaft sections, said cam shaft sections being operated from the flag.

8. A compact assembly for taximeters including a wheel operated shaft, fare drums, means cooperating with the said shaft whereby the fare drums are actuated, a flag operated cam shaft, and a second cam shaft arranged in right angular relation to said other cam shaft and geared thereto, both cam sections having means for controlling the operation of the taximeter.

9. A taximeter including fare drums, a shaft for supporting the same, a star wheel unit also mounted on the shaft, means for operating the star wheel unit, means for resetting the initial fare drum, means for resetting the star wheel unit, and means for locking the resetting means for the initial fare drum and the star wheel unit when the flag is in vacant position.

10. A taximeter including fare drums, a shaft for supporting the same, a star wheel unit also mounted on the shaft, means for operating the star wheel unit, means for resetting the initial fare drum, means for resetting the star wheel unit, and a lever having means for simultaneously locking and releasing the resetting means for the initial fare drum and the resetting means for the star wheel unit.

11. A taximeter including fare drums, a shaft for supporting the same, a star wheel unit also mounted on the shaft, means for operating the star wheel unit, means for reset-

- ting the initial fare drum, said means comprising a gear on the initial drum, a shaft, a gear thereon meshing with the gear on the fare drum, a pinion and a locking cam on the last mentioned shaft, a resetting gear train connecting with said pinion, and a flag controlled lever cooperating with said locking cam to lock the resetting means when the flag is in vacant position. 5
10. 12. A taximeter including fare drums, a shaft for supporting the same, a star wheel unit also mounted on the shaft, means for operating the star wheel unit, means for resetting the initial fare drum, means for resetting the star wheel unit including a gear in the star wheel unit, a stop for said gear, a second shaft, a gear on said second shaft meshing with the gear of the star wheel unit, a pinion on said second shaft, a resetting gear train meshing with said pinion, a locking cam on said second shaft, and a flag controlled lever adapted to engage with said locking cam to lock the second shaft when the flag is in vacant position. 15
20. 13. A taximeter comprising a main fare register unit including fare drums, a star wheel unit, means for actuating the initial fare drum from the star wheel unit, means for resetting the initial fare drum, and means controlled by the flag for locking said resetting means when the flag is in vacant position. 25
30. 14. A taximeter comprising main fare drums, a shaft for supporting said fare drums, a star wheel unit mounted on the shaft, means for intermittently actuating the initial fare drum from the star wheel, a drum resetting shaft operatively connected with the initial fare drum, a star wheel resetting shaft operatively connected with the star wheel, and means for locking said drum and star wheel resetting shafts when the flag is in vacant position. 35
40. 15. A taximeter comprising main fare drums, a shaft for supporting said fare drums, a star wheel unit mounted on the shaft, means for intermittently actuating the initial fare drum from the star wheel, a drum resetting shaft operatively connected with the initial fare drum, a star wheel resetting shaft operatively connected with the star wheel, common means for simultaneously locking and releasing the drum and star wheel resetting shafts, and flag controlled means for operating said common means for locking the drum and star wheel resetting shafts. 45
50. 16. A taximeter comprising main fare drums, a shaft for supporting said fare drums, a star wheel unit mounted on the shaft, means for intermittently actuating the initial fare drum from the star wheel, a drum resetting shaft operatively connected with the initial fare drum, a star wheel resetting shaft operatively connected with the star wheel, 55
60. 17. A taximeter including fare drums, a shaft on which the fare drums are loosely mounted, a star wheel unit loosely mounted on said shaft and including a star wheel and a gear, a clock driven gear unit also loosely mounted on the shaft, clutch means for connecting said clock driven unit with the star wheel unit, means actuated by the movement of the vehicle for actuating said star wheel unit, a clutch device for connecting and disconnecting said last named means with the star wheel unit, said clutch device including a clutch gear loosely mounted on the shaft and constituting part of a clutch for engaging with the star wheel unit, a pivoted lever, a clutch gear carried by said pivoted lever and adapted to engage with said clutch gear loosely mounted on the supporting shaft and means for operating the initial fare drum from the star wheel. 70
75. 18. A taximeter including main fare drums, a shaft for supporting the same, a star wheel unit including a star wheel and a gear loosely mounted on said shaft, a ratchet wheel carried by the initial fare drum, vehicle actuated means for driving the star wheel, a flag controlled clutch device for connecting said means with the star wheel including a pivoted lever, a gear carried by said pivoted lever, a gear loosely mounted on the shaft and having a ratchet disk thereon adapted to be engaged by a spring pressed pawl carried by the star wheel, and a lever actuated by the star wheel and adapted to engage with the ratchet wheel on the initial fare drum. 80
85. 19. A taximeter including a supporting shaft, fare drums mounted on said shaft, the initial fare drum carrying a resetting gear and a ratchet wheel, a star wheel unit loosely mounted on said shaft, flag controlled clutch means for controlling the operation of the star wheel either by the movement of the vehicle or by clock mechanism, a lever adapted to engage with said star wheel, a pawl carried by said lever adapted to engage with the ratchet wheel on the initial fare drum, a restraining lever for engaging said first mentioned lever, means carried by the star wheel for actuating said restraining lever to release the first mentioned lever, and resetting means engaging with the resetting gear on the initial fare drum. 90
95. 20. A taximeter including a supporting shaft, fare drums loosely mounted on said shaft, a ratchet wheel carried by the initial fare drum, a star wheel unit loosely mounted on said shaft, a lever actuated by said star wheel unit for imparting movement to the initial fare drum through the ratchet wheel 100
105. 110. 115. 120. 125. 130.

thereon, a clock mechanism, and means for driving the star wheel unit at differential speeds from the clock mechanism.

21. A taximeter including a supporting shaft, fare drums loosely mounted on said shaft, a ratchet wheel carried by the initial fare drum, a star wheel unit loosely mounted on said shaft, a lever actuated by said star wheel unit for imparting movement to the initial fare drum through the ratchet wheel thereon, a clock mechanism, and means for driving the star wheel unit at differential speeds from the clock mechanism, said means comprising a dual gear unit mounted on the supporting shaft, a clutch for connecting said dual gear unit with the star wheel unit, a pair of levers, gears of different diameter carried by said levers and driven by the clock-work, flag controlled means for permitting one of said levers to be shifted when the flag is moved to a tariff position to connect the gear carried by one of said levers to engage with one of the gears of the dual gear unit, and means for automatically disengaging said gear from the dual gear unit and shifting the gear of the other lever into engagement with the other gear of the dual gear unit.

22. A taximeter including a supporting shaft, fare drums loosely mounted on the supporting shaft, a drum actuating unit loosely mounted on the supporting shaft, means for actuating the initial fare drum from said unit, a clock mechanism, and means for operating the drum actuating unit at a differential rate, said means including flag controlled means for causing the said unit to be operated at one rate, and means for automatically causing the said unit to be subsequently driven at a different rate.

23. A taximeter including a supporting shaft, fare drums loosely mounted on the supporting shaft, a star wheel unit loosely mounted on the supporting shaft, means for actuating the initial fare drum from the star wheel unit, a clock mechanism, and means for operating the star wheel unit at a differential rate, said means including flag controlled means for causing the star wheel unit to be operated at one rate, and means for automatically causing the star wheel unit to be subsequently driven at a different rate.

24. A taximeter including a supporting shaft, fare drums loosely mounted on the supporting shaft, a star wheel unit loosely mounted on the supporting shaft, means for actuating the initial fare drum from the star wheel unit, a clock mechanism, and means for operating the star wheel unit at a differential rate, said means including flag controlled means for causing the star wheel unit to be operated at one rate, and means for automatically causing the star wheel unit to be subsequently driven at a different rate, said means including a pair of levers and a clockwork driven shaft, a slow gear train

consisting of a gear carried by the clock-work driven shaft and one lever and a fast gear train consisting also of a gear carried by the clockwork driven shaft and the other lever, a dual gear lever mounted on the first mentioned shaft and adapted to operatively connect with the star wheel unit, flag controlled means for throwing the slow gear train into engagement with one of the gears of the gear train unit when the flag is turned to a tariff position, means for restraining the fast gear train from operation for a predetermined period, and means controlled by the lever carrying the fast gear train for automatically rendering the slow gear train inoperative.

25. A taximeter including a supporting shaft, fare drums loosely mounted on the supporting shaft, a star wheel unit loosely mounted on the supporting shaft, means for actuating the initial fare drum from the star wheel unit, a clock mechanism, and means for operating the star wheel unit at a differential rate, said means including flag controlled means for causing the star wheel unit to be operated at one rate, and means for automatically causing the star wheel unit to be subsequently driven at a different rate, said means including an initial-rate lever and a subsequent-rate lever, a clockwork driven shaft, slow speed gearing and fast speed gearing respectively carried by the initial rate lever and the subsequent rate lever and clock-work driven shaft, a dual gear unit mounted on the supporting shaft, clutch means for connecting the dual gear unit with the star wheel unit, means for maintaining both the initial and subsequent-rate levers in inoperative position when the flag is in vacant position, means controlled by the flag for releasing the initial rate lever when the flag is turned to a tariff position, and automatic means controlled by the subsequent rate lever for rendering the initial rate lever inoperative.

26. A taximeter including a supporting shaft, fare drums loosely mounted on the supporting shaft, a star wheel unit loosely mounted on the supporting shaft, means for actuating the initial fare drum from the star wheel unit, a clock mechanism and means for operating the star wheel unit at a differential rate, said means including flag controlled means for causing the star wheel unit to be operated at one rate, and means for automatically causing the star wheel unit to be subsequently driven at a different rate, said means including initial and subsequent-rate levers, slow and fast gears respectively carried by said initial and subsequent rate levers, a pendant arm on each of said levers, a weak spring engaging with the pendant arm of the initial rate lever and a strong spring engaging with the pendant arm of the subsequent rate lever, and a shifter lever adapted

to be engaged by said subsequent rate lever to automatically shift the initial rate lever to an inoperative position.

27. A taximeter including a vehicle wheel driven shaft, a flag, a flag-controlled shaft, a counter, and means including a clutch for connecting the counter with the driven shaft when the flag is in an illegal position.

28. A taximeter including a vehicle wheel driven shaft, a flag, a flag-controlled cam shaft, a counter, and means including a clutch for connecting the counter with the initial driven shaft when the flag is in an illegal position.

29. A taximeter including a vehicle wheel driven shaft, a flag, a flag controlled cam shaft, a counter-shaft driven from said vehicle driven shaft, a clutch device mounted on said counter shaft and adapted to be operatively connected therewith, a counter and a counter-actuating lever adapted to be operated by said clutch device when the flag is in an illegal position.

30. A taximeter including a vehicle wheel driven shaft, a flag, a flag controlled cam shaft, a counter shaft-operatively connected with the vehicle driven shaft, a clutch device slidably mounted on the counter shaft, a shifter lever engaging with said clutch disk, a cam on the cam shaft for controlling said shifter lever, a counter and a counter actuating lever operated by said disk when the flag is in an illegal position.

31. A taximeter including a vehicle wheel driven shaft, a counter shaft, gearing between said vehicle wheel driven and counter shafts, a detector counter, a detector counter operating disk slidably mounted on said counter shaft to be connected and disconnected with the gearing for operating the counter shaft, a lever for shifting said disk, and a cam on the cam shaft for controlling the lever.

32. A taximeter including a vehicle wheel driven shaft, a counter shaft, gearing between said vehicle wheel driven and counter shafts, a paid-miles counter, means for operating said paid miles counter including a lever, a sleeve slidably mounted on the counter shaft and adapted to engage with said gearing, pins carried by the sleeve for operating the lever, a shifter lever engaging with said sleeve, and a cam on the cam shaft for controlling said shifter lever, said cam being adapted to connect the sleeve with the gearing while the flag is in tariff position and to disconnect said sleeve when the flag is in vacant.

33. In a taximeter, an extras fare drum, a ratchet operatively connected therewith, an operating lever, a stud, a check pawl mounted thereon, a pawl carried by said lever and adapted to actuate said ratchet, a spring operatively connecting said pawl and check pawl so as to normally urge both said pawl

and check pawl toward said ratchet, and means whereby said lever is actuated by the driver of the vehicle.

34. In a taximeter, a lever, a shaft, a drum mounted on said shaft, a ratchet wheel secured to said drum, a stud support for said lever, a check pawl carried by said support, a pawl carried by said lever, means whereby said pawl and check pawl are urged toward said ratchet, and means whereby said lever may be manually operated so as to rotate said ratchet through said pawl.

35. In a taximeter, a stud, a lever and a check pawl mounted on said stud, a pawl carried by said lever, a shaft, a drum and a ratchet operatively connected and mounted on said shaft, means whereby said check pawl and pawl are urged toward said ratchet, means whereby said pawl and check pawl are withdrawn from said ratchet, and means whereby said lever is actuated to indicate the extra fares charged the passenger.

36. In a taximeter, a stud, a lever and a check pawl mounted on said stud, means whereby said lever is actuated so as to oscillate its upper end, a pawl carried by said lever, a shaft, a drum and a ratchet mounted on said shaft, means whereby said pawl and check pawl are normally urged toward said ratchet, a flag, a cam shaft operated thereby, and means carried by said cam shaft whereby said lever is rendered inoperative and said check pawl and pawl are disengaged from said ratchet.

37. In a taximeter, an arm adapted to be manually actuated, a stud support, a lever fulcrumed on said support and actuated by said arm, a check pawl in the form of a bell crank lever fulcrumed on said support, a pawl carried by said lever, a shaft, a drum and a ratchet carried by said shaft, said drum and ratchet being operatively connected, means whereby said pawl and check pawl are urged toward said ratchet, a flag, a cam operated thereby and adapted to engage said lever and check pawl so as to rotate the lever and check pawl away from said ratchet.

38. In a taximeter, a main supporting shaft, a star wheel carried thereby, means whereby said star wheel is operated either by a moving part of the vehicle or by a time driven mechanism, fare drums mounted on said main supporting shaft, a second shaft, a lever mounted on said second shaft adapted to be oscillated by said star wheel, a detent carried by said lever, a ratchet operatively connected with one of said fare drums and adapted to be actuated by said detent, a flag, means operated by said flag whereby said lever is withdrawn from said star wheel when the flag is in vacant position, a restraining lever provided with a notch, and means carried by said lever adapted to be engaged by said notch when said lever is moved to inoperative position.

39. In a taximeter, a main supporting shaft, a star wheel carried thereby, means whereby said star wheel is operated either by a moving part of the vehicle or by a time driven mechanism, fare drums mounted on said main supporting shaft, a second shaft, a lever mounted on said second shaft adapted to be oscillated by said star wheel, a detent carried by said lever, a ratchet operatively connected with one of said fare drums and adapted to be actuated by said detent, a flag, means operated by said flag whereby said lever is withdrawn from said star wheel when the flag is in vacant position, a restraining lever provided with a notch, and means carried by said star wheel to engage said restraining lever and disconnect it from the first mentioned lever when the flag is moved to a tariff position.

40. A taximeter provided with fare drums and including differential time driven mechanism, said time driven mechanism including a plurality of gears, an initial rate lever and a subsequent rate lever, a gear carried by each of said levers, a shaft driven by a clock, gears on said shaft having different pitch ratios and meshing with the gears carried by said levers, and means whereby the gears on said levers are successively caused to mesh with the first mentioned gears, and means operatively connecting the first mentioned gears with said drums.

41. In a differential time driven mechanism for taximeters provided with fare drums, a supporting shaft, a plurality of gears thereon, an initial rate lever, a gear carried thereby, a shaft driven by a clock, time gears having different pitch ratios secured to said shaft driven by the clock, the smaller of said last mentioned time gears meshing with the gear carried by the initial rate lever, a subsequent rate lever, a gear carried thereby and meshing with the larger of said time gears, and means whereby the gears carried by the said levers may be subsequently engaged by the first mentioned gears, and means operatively connecting the first mentioned gears with said drums.

42. In a differential time driven mechanism in a taximeter provided with fare indicating means, an initial rate lever and a subsequent rate lever, a gear carried by each of said levers, a time shaft, time gears having different ratios carried by said time shaft and meshing respectively with the gears carried by the levers, a supporting shaft, gears thereon, cam means whereby said levers may be held in such a position that the levers carried thereon are out of mesh with the gears on the supporting shaft, spring means tending to urge the gears on the levers toward the gears upon the supporting shaft, said initial rate lever being moved by its spring so that the gear carried thereby will mesh with one of the gears on the supporting shaft when the

cam means no longer restrains it, and restraining means whereby the subsequent rate lever is restrained from such movement while the gear carried by the initial rate lever is in mesh with one of the gears on the supporting shaft, means whereby the restraining means is removed so that the gear carried by the subsequent rate lever meshes with its gear on the supporting shaft, and means whereby the initial rate lever is simultaneously moved so that the gear carried thereby is caused to unmesh with its gear on the supporting shaft.

In testimony whereof I hereunto affix my signature.
